UNITED STATES PATENT OFFICE.

JOHN J. PLESSMAN, OF OAKLAND, CALIFORNIA, ASSIGNEE OF ONE-HALF TO ALFRED JOHNSON, OF OAKLAND, CALIFORNIA.

MOLDING MACHINE.

Application filed November 8, 1921. Serial No. 513,632.

To all whom it may concern:

Be it known that I, JOHN J. PLESSMAN, a citizen of the United States, residing at Oakland, in the county of Alameda and State of California, have invented certain new and useful Improvements in Molding Machines, of which the following is a specification.

My invention is a molding machine, particularly useful for molding window sash weights, and other chilled cast castings.

The invention is particularly directed to a machine for simultaneously operating a plurality of molds in such a way that perfect castings may be readily produced in large numbers.

Referring to the annexed drawing in which my invention is illustrated and which forms a part of this specification:

Figure 1 is a side elevation of my molding machine.

Figure 2 is an end elevation of my molding machine.

Figure 3 is an inside view of one of the movable mold members.

Figure 4 is a vertical section of said movable mold member taken on line 4—4 of Figure 3.

Figure 5 is a vertical section taken on line 5—5 of Figure 4 showing the coupling plates for coupling the movable mold members to the shaft.

Figure 6 is a side view partly in section of a modified form of my invention.

In the drawing 1 and 2 indicate two end standards which are bolted upon two beams 3 and 4 near the ends of said beams respectively. Each standard 1 and 2 is formed with an inner vertical flange 5 and a horizontal flange 6 extending outwardly from the upper end of said vertical flange. Angle irons 7 and 8 are mounted at their ends on the standards 1 and 2, the vertical flange of each of said angle irons resting against

the inside of one of the flanges 5 and the horizontal flange of each of said angle irons resting upon one of the flanges 6 of the standards 1 and 2. The vertical flanges of said angle irons are bolted by bolts 9 to the vertical flanges 5 of the standards 1 and 2 and the horizontal flanges of said angle irons being bolted by bolts 10 to the flanges 6 of said standards. Bearings 11

and 12 are bolted by bolts 13 to the upper part of the standards 1 and 2. A shaft 14 extends longitudinally of the machine through the bearings 11 and 12 and has a thread 15 at one end which engages a thread inside the bearing 11. On the threaded end of said shaft is secured a hand wheel 16 for turning the shaft. The shaft 14 extends through openings 17 in a plurality of molds 18, each of which molds is separated into two members 19 and 20, which members have side horizontal flanges 21 and 22 resting on the horizontal flanges of the angle irons 7 and 8 respectively. In each of the mold members 19 and 20 is one half of a plurality of window sash weight impressions 23 into which the molten iron is poured to mold the sash weights, said impressions being arranged in pairs, communicating at their upper ends with mouths 24 in the top of the molds, one half of said mouths being in each mold member. The mold members 20 are stationary, being secured to the angle irons 7 and 8 by bolts 25 extending through the flanges 21 and 22 and the horizontal flanges of said angle irons. The shaft 14 has a plurality of annular grooves 25', and a pair of plates 26 and 27 provided with notches 28 and 29 are bolted to the outside of each mold member 19 by bolts 30 and 31 respectively, with said notches surrounding said shaft and the edges of said notches resting in said grooves, and the notched edges of said plates resting adjacent each other. Upon turning the shaft 14 by the hand wheel 16, the screw 15 causes the mold members 19 to move toward or away from the mold members 20 to close or open the molds.

A collar 32 is secured to the shaft 14 adjacent the plates 26 and 27 and a spring 33 is positioned between said collar and plates. The object of this construction is to allow for expansion of the mold and of the metal within the mold.

In the modified form of my invention shown in Fig. 6, the screw 15 and hand wheel 16 is replaced by a hydraulic cylinder 35, the piston 36 of which is secured to the shaft 14. The shaft 14 is moved forward or backward as the pressure is applied to either side of the piston 36.

From the foregoing description it will

be seen that a plurality of molds may be incorporated in this machine, all of which are yieldably simultaneously closed, and individually yieldably held closed. This invention therefore includes the many desirable features of multiple mold casting machine and is so made that many of the parts and complexities have been eliminated which are present in similar machines known to the art at this time. Its flexibility, simplicity and ability to produce castings rapidly are its outstanding features.

The individually yieldably and multiple operable feature makes it possible to open or close all molds simultaneously. The yieldable feature is important. In the pouring of the molds one of them may be filled, the material may expand and slightly open that particular mold due to the yieldable spring feature without tending to force open the other molds which are yet to be filled. If this yieldable feature is not used and a plurality of molds are rigidly connected to the operating shaft the filling and cooling of the material in one mold would tend to slightly open the remaining molds, possibly before they could be filled, and thus cause waste of metal through the cracks between the parts of the mold.

Having described my invention, I claim:

1. In a molding machine, a series of molds, each comprising two members, one member of each mold being stationary and the other being movable, a shaft to which the movable member of each mold of said series is individually yieldably connected, and operating means on said shaft for moving it to cause said movable mold members to move against or away from the stationary members to respectively open or close the mold.

2. In a molding machine, a mold, comprising two members, a first movable member and a second member, a third member movable with respect to said second member, a shaft extending through said first and second members and connected to said third member to move the same, a collar on said shaft adjacent said first movable member, and means on said shaft for causing said first movable member to move against or away from said second member.

3. In a molding machine a supporting frame, a series of molds mounted in tandem on said frame, each of said molds composed of at least two parts, one of which is rigidly attached to said frame and one of which is movable, and an operating shaft extending lengthwise of said frame and passing through each of said molds, said shaft being yieldably attached to said movable mold parts and constituting single connecting means for simultaneously adjusting said movable members.

4. In a molding machine, a support, a

plurality of molds mounted on said support, and means for simultaneously yieldably closing said molds and individually yieldably holding them closed.

5. In a molding machine, a support, a plurality of molds mounted on said support, and means for simultaneously closing said molds and individually yieldably holding them closed.

6. In a molding machine a supporting frame composed of two members spaced apart to form a track, a series of molds mounted in tandem on said track, each of said molds composed of two parts, one of said parts being movable along said track and the other being rigid with said track, a shaft extending through said molds, journals attached to said supporting frame and having said shaft journaled therein, yieldable means attached to said shaft and to said movable mold parts, said shaft and said yieldable means, constituting means to simultaneously yieldably adjust said mold members with respect to each other.

7. In a molding machine, standards, two angle irons mounted on said standards, a bearing mounted on each standard, a shaft extending through said bearings, a thread on said shaft engaging a thread in one of said bearings, a plurality of molds through which said shaft extends, each mold comprising a stationary member and a movable member, and means for coupling said shaft to the movable member of said molds so that said movable member will be moved against or away from said stationary members when said shaft is rotated one way or the other.

8. In a molding machine, a rectangular frame, means for supporting said frame, a rotatable shaft positioned parallel with the longer members of said frame and journaled midway of the length of the shorter members of said frame, a plurality of two piece molds supported at their ends in parallel positions and having openings through which said shaft passes, one part of each of said molds being bolted to said longer frame members and the other part being movable with respect to said first part by means of said shaft, means for connecting said shaft to said movable part constituting a yielding connecting means allowing the said movable parts to yield under undue pressure, and means for rotating said shaft, said last named means causing the shaft to be moved lengthwise.

9. The combination as expressed in claim 8 characterized by a coil spring, a collar on said shaft, a groove in said shaft, and a flat ring mounted in said groove so as to be engaged on one side by said spring and on the other side by one of said movable parts.

10. The combination as expressed in claim 8 characterized by a collar on said

shaft, spaced from each of said movable parts, a coil spring located around said shaft and engaging said collar at one end, the other end of said spring tending to exert pressure on one of said movable parts, a groove in said shaft and two notched plates secured to said movable member so that the notches will closely fit said grooved part of said shaft, all of these latter elements constituting the yielding connection above mentioned.

In testimony whereof I affix my signature.

JOHN J. PLESSMAN.
